UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

TAKE-UP MECHANISM FOR SHOE-SEWING MACHINES.

1,118,522.

Specification of Letters Patent.

Patented Nov. 24, 1914.

Application filed May 2, 1908. Serial No. 430,612.

To all whom it may concern:

Be it known that I, HARRIE A. BALLARD, of Boston, in the county of Suffolk and State of Massachusetts, have invented certain new and useful Improvements in Take-Up Mechanism for Shoe-Sewing Machines, of which the following is a specification.

This invention relates to shoe-sewing machines, and has for its object to provide a takeup mechanism of an improved character for a machine of this type.

The attainments sought by the invention are first, smoothness of action of the takeup as a preventive of breaking the thread, second, rapidity of operation in drawing off excess thread, and third, increase in speed of the machine as a whole by reason of the mechanical perfection of the said mechanism. The first of these attainments is the result of so organizing the mechanism as to impart an initially minimum and gradually increasing degree of actuation in taking up the thread. In other words the speed of the takeup increases from zero to maximum in its course of operation and so does not subject the thread to a shock as if by a suddenly applied tension. The second attainment is the result of the first in that the accelerating action of the takeup permits a greater range of movement without breaking the thread, and the third may be said to be the result of the first two.

The actuating mechanism of the present invention is adapted to effect an extremely rapid drawing of the thread and a somewhat slower delivery of the same. This is especially adapted to lock stitch machines for the purpose of drawing down a newly formed stitch from the path of the continuously moving shuttle.

Referring now to the drawings forming a part of this specification, Figure 1 is a right side elevation of a portion of a shoe sewing machine equipped with a takeup mechanism constructed in accordance with this invention. Fig. 2 is an elevation of the takeup mechanism detached and in a different position. Fig. 3 is a section on line 3—3 of Fig. 1. Fig. 4 is a perspective of a thread-locking device. Fig. 5 is a sectional plan view of the takeup. Fig. 6 is a section on line 6—6 of Fig. 5. Fig. 7 is a left side elevation of a fragment of the takeup. Fig. 8 is a

modified form of a detail of the actuating mechanism.

The drawings are made with a view to presenting the takeup mechanism in the clearest manner, and for that reason certain parts of the machine are purposely omitted.

The same reference characters indicate the same parts wherever they occur.

Referring first to Fig. 1, 10 represents the upper portion of a standard on which is mounted a head 11. In the head is journaled a continuously rotating power shaft 12 by means of which the several instrumentalities are actuated.

13 is a curved needle mounted in an oscillatory carrier 14, and 15 is the casing inclosing a continuously rotating shuttle (not shown) which co-operates with the needle in forming the stitches. The needle carrier 14 is mounted upon a stud 16 at the extremity of the arm 17 of a carriage 18. The carrier 14 is also provided with an awl 19 which is arranged in the same arc as the needle and which, as shown by Fig. 1, is in the sole of a shoe *a*. The carrier is oscillated by suitable means and, when it turns so as to introduce the awl into the work (see arrow), the pressure upon the work is resisted by a presserfoot 20. The presserfoot is affixed to an oscillatory carrier 21 pivotally mounted at 22 upon a suitable stationary support.

In addition to the presserfoot, the carrier 21 is provided with a thread roll 23, and co-operating thread-locking members 24 and 25. The member 24 is a shoulder formed upon the carrier and the member 25 is an arm pivotally mounted at 26 and adapted to swing toward and from the shoulder 24 and alternately clamp and release a thread extending between them. These locking members are shown in detail in Figs. 2 and 4 in which the arm 25 has a slot 27 which is occupied by the arm 28. This arm is affixed to a rockshaft 29 which has an operating arm 28' coacting with a cam 28''. The slot 27 and arm 28 are curved in an arc of which the center is coincident with the fulcrum 22, and so the relation of the said slot and arm is not disturbed by rocking movement of the presserfoot carrier 21.

30 is an oscillatory arm which is in effect a carrier for thread-guiding rolls 31 and 32. The carrier is mounted upon a stationary

fulcrum 33 in the head 11 and has an extension arm 34 by which it is connected with an actuator 35. The actuator is in the form of a wrist pin carried by a continuously 5 rotating shaft 36, and it operatively engages the arm 34 by occupying a slot 37 formed in the latter. The slot is substantially radial but it has an offset whose function is to effect a momentary dwell of the 10 arm during a portion of the revolution of the actuator. The shaft 36 is mounted in the head 11 and carries a gear 38 which is driven by an intermeshing gear 39 affixed upon the shaft 12.

15 The thread α , presumably a waxed thread, is drawn from a suitable source of supply (not shown) and passes in the following order between the locking members 24 and 25 over roll 23, takeup roll 31, yielding takeup roll 40, the takeup roll 32 and thence to the needle. A looper (not shown) and any other instrumentality may be presumed to be interposed between the roll 32 and the work for completing the stitch-forming 20 mechanism.

25 The yielding takeup roll 40 is mounted at the free end of an arm 41 formed with a stem or spindle 42 and mounted in any suitable way in a stationary bearing. The bearing 30 illustrated is by means of a plate 43 attached to the casing 44 of a steam heating chamber 45. One end of the stem 42 is squared and has a collar 46 to which is attached one end of a coiled clock spring 47. 35 The other end of the spring is attached to the plate, see Fig. 6, and has a tendency to turn the stem so as to move the free end of the arm 41 toward a fixed stop 48 formed on the plate. A similar stop 49 also formed 40 on the plate limits movement of the arm in the opposite direction. In order to provide means of adjustment for the yielding takeup, the plate 43 is provided with slots 50 through which extend the screws 51 which 45 clamp the plate against the steam casing. By this means the takeup arm 41, as well as the plate, may be adjusted relatively to the takeup rolls 31 and 32.

50 The operation of the takeup may be followed by referring first to Fig. 1 in which the needle 13 is at or near the end of its up stroke, having drawn all excess thread from the takeup and through the work. At this time the thread is clamped between the locking members 24 and 25, and the takeup arm 30 is at the end of the delivery stroke and at the beginning of the takeup stroke. The said arm is, however, momentarily stationary because the actuator 35 is moving in a 55 direction substantially radial to the axis 33 of the takeup arm, having just passed through a portion of the slot 37 which is concentric to the actuator's axis of rotation.

60 During the stationary period of the takeup the shuttle (not shown) contained in the

shuttle race 15 passes through the loop of thread recently drawn up by the needle, and upon the passing of the shuttle the actuator 35 moves into the radial portion of the slot 37, meanwhile approaching the axis 33. 70 The arms 30 and 34 therefore begin to move gradually through the takeup stroke which constantly increases in speed as the individual movements of the actuator and the arm 34 approach parallelism. By this action of the takeup arm the thread is drawn down from the path of the shuttle with a corresponding ratio of speed and when drawn tightly against the sole of the shoe the new stitch is completed. The actuator 75 meanwhile continues to the position shown by Fig. 2, and thereby moves the takeup to the end of the takeup stroke and the beginning of the delivery stroke. During the latter part of the takeup stroke the quantity of thread is so reduced as to draw the yielding takeup away from the stop 48 and in opposition to the spring 47, but immediately after being drawn down as shown by Fig. 2, the thread is momentarily released by the 80 members 24 and 25, and the arm 41 thereupon springs back to the stop 48 thereby drawing a fresh quantity of thread from the supply. At this point in the operation the takeup arms 30 and 34 receive no appreciable movement from the actuator whose direction of movement is again substantially radial to the axis 33. It may be assumed that during the last described period occurs the operation of those instrumentalities, 85 hereinbefore mentioned but not shown, which lay the thread about the needle preparatory to a new stitch. The needle, now at its lower position starts back through the work at the same time that the takeup arm 30 starts to return to its former position shown by Fig. 1, and so a full cycle of movements is completed.

90 To restate the coöperate actions of the actuator 35 and the arm 34, rotation of the 95 former at a constant rate of speed produces gradually increasing and diminishing speed in the movement of the latter. If it should be desirable to augment the variation in the speed of the takeup the result may be readily 100 attained by substituting eccentric gears 52 and 53 instead of the gears 38 and 39, see Fig. 8. In the event of such substitution, the speed of the rotating actuator would be continually increasing and diminishing, and 105 when correctly timed with relation to the arm 34, the effect would be a greater increase and diminution in the speed of the takeup.

110 Having thus explained the nature of my 115 said invention and described a way of constructing and using the same, although without attempting to set forth all of the forms in which it may be made or all of the 120 modes of its use, I declare what I claim 125 is:—

1. A takeup comprising a fulcrum, a takeup arm arranged to rock upon said fulcrum, said takeup arm having a slot, a crank pin movable in said slot, for oscillating said arm, the median line of the takeup portion of said slot being substantially radial with relation to said fulcrum, means for carrying said crank pin in a circular path, a rotatable member, and transmission means for transmitting rotation from said member to said carrying means, said transmission means having provisions for causing increasing and diminishing speed of said crank pin relatively to said member.
- 5 2. A takeup mechanism comprising an oscillatory takeup arm, and a crank pin for operating the same, said arm having a substantially radial face for engaging said crank pin to effect the takeup movement, and a curved face to effect a dwell prior to each takeup movement.
- 10 3. A takeup mechanism comprising a slotted takeup arm, a crank pin movable in the slot of said arm for oscillating the arm, and eccentric gears for driving said crank pin at varying speed.
- 15 4. A takeup mechanism comprising an oscillatory takeup arm, and a crank pin movable in a circular path, said arm having a slot for said crank pin, said slot having a substantially radial face for effecting the takeup movement, and a non-radial face for effecting the return movement and a dwell.
- 20 5. The combination with an oscillatory main takeup, of a thread clamp, a crank pin revolving continuously in one direction, means operated by said crank pin for reciprocating the main takeup with a retardation in each cycle of movements, actuating
- 25 means for said thread clamp arranged to open it during the retardation of the main takeup, and a yielding takeup adapted to be retracted by the action of the main takeup and to draw thread when the thread
- 30 clamp is opened.
- 35 6. The combination with a main takeup, and means for reciprocating the same; of a spring-actuated takeup disposed to be retracted by the takeup movement of the main takeup, a thread clamp, and means for operating said clamp so as to clamp the thread during the latter part of the takeup movement of the main takeup and release the thread when the main takeup is at the end of its takeup stroke, said spring-actuated takeup being arranged to draw fresh thread from said clamp.
- 40 7. A shoe-sewing machine comprising in combination, stitch-forming mechanism, a main takeup and operating means therefor, means arranged to clamp the thread until the thread-pulling stroke of said takeup is completed, and a spring takeup arranged to be retracted by the action of the thread due to said stroke of the main takeup, said clamping means being arranged to release the thread and said spring takeup being arranged to pull thread from said clamping means while said takeup is substantially stationary.
- 45 8. A shoe-sewing machine comprising in combination, stitch-forming mechanism, a main takeup and operating means therefor, means arranged to clamp the thread until the thread-pulling stroke of said takeup is completed, and a spring takeup arranged to be retracted by the action of the thread due to said stroke of the main takeup, said clamping means being arranged to release the thread and said spring takeup being arranged to pull thread from said clamping means before said main takeup has traversed any substantial part of its return or thread-delivering stroke.

In testimony whereof I have affixed my signature, in presence of two witnesses.
